UNITED STATES PATENT OFFICE.

TELFORD CLARENCE BATCHELOR, OF HAY MILLS, NEAR BIRMINGHAM, ENGLAND.

WIRE ROPE.

1,137,690.

Specification of Letters Patent. Patented Apr. 27, 1915.

Application filed January 29, 1914. Serial No. 815,278.

To all whom it may concern:

Be it known that I, TELFORD CLARENCE BATCHELOR, a subject of the King of Great Britain, residing at Hay Mills, near Birmingham, England, have invented certain new and useful Improvements in Wire Ropes, of which the following is a specification.

- The present invention relates to improvements in wire ropes, and it has for its object primarily to provide a stranded rope containing a relatively large area of effective wire with corresponding degree of strength as compared with other ropes as heretofore constructed and containing the same quantity and quality of material, to provide a rope which will be non-spinning, and one in which the internal friction is reduced to a minimum.
- According to this invention I take what is known as a locked coil wire rope and I cover same with one or more concentric layers of flattened or other strands of wire, the flattened or other strands each comprising a plurality of wires twisted together and being coiled about the locked wire rope with the coils in the same direction as the outer layer of wire of the locked coil rope or opposite thereto.
- The annexed drawings show one example of how my rope is made up.
- Figure 1 is a section, Fig. 2 side elevation, and Fig. 3 is a side elevation showing a portion of a locked coil wire rope and one of the flattened exterior strands applied thereto.
- In the embodiment of the invention shown in the accompanying drawing, A indicates generally the locked coil wire rope and B the layer of flattened twisted strands covering the exterior thereof, as shown clearly in Figs. 1 and 2. The locked coil wire rope is shown in Fig. 3 as built up of an interior or central round core wire C, the layers D, E, F, G, H laid successively upon one another in a spiral direction with reference to the

length of the rope, and I and J represent alternating round and locking wires which present a relatively smooth unbroken exterior, as appears clearly in Figs. 1 and 3. 50 Each of the strands B is composed of a plurality of wires B' which are twisted together, and the strands B are flattened and laid upon the smooth unbroken exterior of the locked coil wire rope. These strands B 55 are laid spirally upon the locked coil wire rope and are sufficiently close to cover the exterior thereof. It is to be understood that in Fig. 3 all but one of the flattened exterior strands are removed in order to illustrate 60 more clearly the form of each strand.

In constructing a rope in the manner described above, the locked coil wire rope presents a smooth or unbroken exterior surface against which the flat sides of the flattened 65 exterior strands are laid, insuring minimum wear by friction between the interior locked coil wire rope and the exterior strands, and it presents the advantage of providing a stranded rope containing an increased area 70 of effective wire and consequently increased strength for a rope of a given size and weight.

What I do claim as my invention and desire to secure by Letters Patent is:— 75

The combination of a locked coil wire rope presenting a relatively smooth unbroken exterior and an exterior layer of strands coiled about the locked wire rope, each of said strands comprising a plurality of wires 80 twisted together and each strand being flattened with one of its flat sides lying against the relatively smooth unbroken exterior of the locked coil wire rope.

In testimony whereof I have hereunto set 85 my hand in presence of two subscribing witnesses.

TELFORD CLARENCE BATCHELOR.
